UNITED STATES PATENT OFFICE

127,603

DESIGN FOR A COMBINATION TIP AND HOLDER FOR BROOM HANDLES AND THE LIKE

Burr Nickle, Butler, Pa.

Application March 7, 1941, Serial No. 99,417

Term of patent 14 years

To all whom it may concern:

Be it known that I, Burr Nickle, a citizen of the United States, residing at Butler, in the county of Butler, State of Pennsylvania, have invented a new, original, and ornamental Design for a Combination Tip and Holder for Broom Handles and the Like, of which the following is a specification, reference being had to the accompanying drawing, forming a part thereof.

Figure 1 is a side view of a combination tip and holder for broom handles and the like embodying my new design; and Fig. 2 is a top plan view thereof.

I claim:

The ornamental design for a combination tip and holder for broom handles and the like, as shown.

BURR NICKLE,
